Primary Examiner — Elizabeth J Oswecki(74) *Attorney, Agent, or Firm* — McAndrews, Held & Malloy, Ltd.(57) **CLAIM**

The ornamental design for an electronic chip card, as shown and described.

DESCRIPTION

FIG. 1 is an isometric view of an electronic chipcard for a telephone showing my new design;

FIG. 2 is a front view thereof;

FIG. 3 is a left side view thereof, a right side view being identical thereto;

FIG. 4 is a rear view thereof; and,

FIG. 5 is a bottom view thereof, a top view being identical thereto.

The broken lines shown in the drawings represent portions of the electronic chip card that form no part of the claimed design.
